UNITED STATES PATENT OFFICE.

JOHN C. SMITH, OF CHICAGO, ILLINOIS.

DESIGN FOR AN ELECTRIC-LIGHT GLOBE.

Application filed December 13, 1924. Serial No. 11,691. Term of patent 14 years.

To all whom it may concern:

Be it known that I, JOHN C. SMITH, a citizen of the United States, residing in Chicago, county of Cook, and State of Illinois, have invented a new, original, and ornamental Design for an Electric-Light Globe, of which the following is a specification, reference being had to the accompanying drawing, forming a part thereof.

Figures 1 and 2 are top and side views respectively of an electric light globe showing my new design.

The invention consists of a globe substantially of spherical form with circular flat side faces merging directly into the spherical surface of the globe and a bull's-eye in the central portion of each flat face.

I claim:

The ornamental design for an electric light globe as shown and described.

JOHN C. SMITH.
